[57] CLAIM

The ornamental design for a combined air filter assembly and canister for an antique automobile, as shown and described.

DESCRIPTION

FIG. 1 is a front elevational view of a combined air filter assembly and canister for an antique automobile showing my new design, the canister wall being shown partially broken away to show the inside of the canister;

FIG. 2 is a bottom elevational plan view thereof; FIG. 3 is a top elevational plan view thereof; FIG. 4 is a perspective plan view of FIG. 1 with the canister having the cover-lid in place thereon;

FIG. 5 is a top elevational plan view of FIG. 1 thereof; FIG. 6 is a bottom elevational plan view of the cover-lid thereof;

FIG. 7 is a modified front elevational plan view of FIG. 1 of a combined air filter assembly and canister for an antique automobile in a condition without the canister sidewall portion as externally removably connected therewith;

FIG. 8 is a bottom elevational plan view in FIG. 7 thereof; FIG. 9 is a top elevational plan view thereof; FIG. 10 is a perspective view of the canister portion with cover-lid thereon;

FIG. 11 is a top elevational plan view of the canister in FIG. 10 thereof; FIG. 12 is a perspective view of a combined air filter assembly and canister for an antique automobile with the canister portion shown in FIG. 7 connected thereto;

FIG. 13 is a modified front elevational plan view of FIG. 1 of a combined air filter assembly and canister for an antique automobile in a condition without the canister sidewall cylinder portion as externally removably connected therefor; FIG. 14 is a bottom elevational plan view of FIG. 13 thereof; FIG. 15 is a top elevational plan view of FIG. 13 thereof; FIG. 16 is a perspective view of the cylinder canister portion thereof;

FIG. 17 is a top elevational view of the a combined air filter assembly and canister for an antique automobile in FIG. 16 with removable cover-lid assembly connected thereto; and, FIG. 18 is a perspective view of the assembled a combined air filter assembly and canister for an antique automobile as shown in FIG. 13 with the assembly canister and cover thereon.

The rear view of FIGS. 1, 4, 7, 10, 12, 13, 16 and 18 is mirror image respectively, thereof.
